SOCKET ARM FOR LIGHT REFLECTING SHADES

Filed Aug. 6, 1928

Michael B. Bowen
INVENTOR.

BY

G. Loring Miller
ATTORNEY.

UNITED STATES PATENT OFFICE.

MICHAEL B. BOWEN, OF DECATUR, ILLINOIS, ASSIGNOR TO FARIES MANUFACTURING COMPANY, OF DECATUR, ILLINOIS.

SOCKET ARM FOR LIGHT-REFLECTING SHADES.

Application filed August 6, 1928. Serial No. 297,713.

My invention relates to improvements in socket arms in which the principal object is to maintain the source of light as near the center of a light reflecting shade as possible, 5 consistent with convenient and practical wiring and assembling, and in consideration of adaptation to a minimum sized light reflecting shade of conventional type.

The objects of my improvement are:

10 1. To provide a socket arm of this type so devised as to require a minimum amount of machining and handling in the course of its production or manufacture.

15 2. To provide such features of construction in my improved socket arm as will permit the ready and simple attachment thereto of a known make of electric socket, although I desire it to be understood that no claim is made to said electric socket, as a 20 whole or any part thereof nor to its combined use with my invention.

25 3. To provide means for attaching said known make of electric socket to my invention in such a manner as to positively insure the downward position of the pull chain eyelet on said socket so that the pull chain will always hang from the under side of the same.

These and other objects are attained by the mechanism illustrated in the accompanying 30 drawings in which:

Fig. 1 is a side elevation showing the device in use upon a conventional lamp, a portion of the light reflecting shade being broken away to reveal the details of a typical installation.

Fig. 2 is a plan view, a portion of the light reflecting shade being broken away to show the device installed as in Fig. 1.

Fig. 3 is a view taken from the normal top 40 of the device.

Figs. 4 and 5 are views of opposite ends of the device as shown in Fig. 3.

Corresponding numerals refer to corresponding parts throughout the several views.

45 The improved socket arm described in this application is secured to a lamp by means of the threads 10 on one end thereof, this feature being acknowledgedly old and immaterial to the present invention.

50 This device is made preferably of cast metal, brass, for example, as it may thus be easily made in one piece in a single casting operation of which the economic advantages are obvious.

55 The right angle shaped channel arm 11

forms a suitable open conduit for the electric wires 11—A leading to the threaded electric socket 11—B engaged at one end of said right angle shaped channel arm 11 by means of the fingers 12, 13 and 14, which are arranged 60 for spaced engagement by and between the said threaded electric socket 11—B and its threaded collar 11—C. The finger 13 is provided with a right angle projection 13—A which serves to prevent said threaded electric 65 socket 11—B from turning or twisting, thereby preventing the possibility of damage to the insulation on the electric wires 11—A as well as insuring the uniform position of every 70 socket in consideration of quantity production in the manufacturing and assembling of this improved socket arm for portable electric lamps.

Apart from the necessary act of wiring the 75 socket to be used it will be noted that no screws or other separate parts are requisite to the securing of this device to the socket and that the same may be assembled simply by the use of the assembler's hands without tools.

In the practical application of this device 80 to a portable electric lamp, the threads 10 on one end of said channel arm 11 are brought into engagement with corresponding threads in a suitable fitting upon the lamp and turned up until channel arm 11 is in the desired position for wiring and the attachment of the threaded socket 11—B and its threaded collar 11—C. Said threaded socket 11—B is then held in position against the fingers 12, 85 13 and 14, and said threaded collar 11—C is then slipped over said fingers 12, 13 and 14 into threaded engagement with said threaded 90 socket 11—B.

Said threaded collar 11—C may then be 95 turned up tightly, thus holding in firm engagement said fingers 12, 13 and 14.

The advantages of my improved socket arm will appear readily evident, especially considering its features of practical utility combined with economic production and installation.

Having thus described my invention, what I regard as new and desire to secure by Letters Patent is:

1. In a socket arm substantially as described, an arm having a channel or groove extending from one end to the other thereof, means on one end of said arm for engaging a threaded collar socket, said means com- 110

prising a plurality of fingers adapted to engagement by and between a threaded socket and a correspondingly threaded collar for the same.

- 5 2. In a socket arm substantially as described, a right angle shaped arm formed in a groove or channel along its entire course, a plurality of spaced fingers integral with one end of said arm, said fingers adapted to lie flat against the normal top of a threaded socket so that a correspondingly threaded collar when brought into threaded engagement with said socket will thereby engage the outer extremities of said fingers.
- 10 15. 3. In a socket arm substantially as de-

scribed, a right angle shape arm formed in a groove or channel along its entire course, three flat, spaced fingers integral with one end of said arm, one of said fingers having its extremity formed into a short projection or lug extending at right angles therefrom, said fingers adapted to lie flat against the normal top of a threaded socket so that a correspondingly threaded collar when brought into threaded engagement with the normal top of said socket will thereby engage the outer edges of said fingers. 20 25

In testimony whereof I have signed the foregoing specification.

MICHAEL B. BOWEN.
